UNITED STATES PATENT OFFICE

2,009,082

SHOE HEEL

Jack F. Esterson, Baltimore, Md.

Application June 1, 1932, Serial No. 614,819

7 Claims. (Cl. 36—36)

My invention relates to apparatus for and methods of removably interlocking a main and a replaceable heel section, and more particularly, to novel apparatus for and methods of mechanically interlocking lifts to the main body of the heel.

It has been proposed to mechanically interlock lifts with heel sections by mechanical members. These have never gone into practical use, however, because the complexity of the mechanism required special skill and tools to engage and disengage the members; they required varied sizes and shapes to fit the numerous sizes and shapes of heel sections making the costs prohibitive; they utilized groove fitting, requiring extreme precision in the manufacture, or they were loosely fitted permitting movements of one section with respect to the other resulting in strains and accordingly, in a likelihood of accidental separations of the sections; they did not permit a snug fit between the main section of the heel and the lift; they required the exposure of considerable metal, making the heel unsightly and they failed to take cognizance of the main stresses and strains occurring in the normal walking postures of the wearer, resulting in accidental separation of the lift from the heel section.

Accordingly, an object of my invention is to provide mechanical interlocking means overcoming these objections.

A further object of my invention is to provide novel mechanical interlocking means for shoe lifts which are independent of the size and shape of the heel.

35 A further object of my invention is to provide novel means for firmly pressing the engaging surface of the lift against the engaging surface of the heel, particularly sealing its edges against the admission of foreign matter.

40 Still a further object of my invention is to provide novel mechanical interlocking means for a lift which are not visible and which are contained wholly within the edges of the heel members.

45 Still another object of my invention is to provide novel mechanical interlocking means requiring substantially no precision of parts.

As the foot is lifted and brought forward and 50 upward in walking, the heel may encounter an obstruction. This impact with the obstruction ordinarily occurs at the breast of the heel and in striking the lift has, with constructions heretofore proposed, separated the lift from the main 55 heel section. I have discovered that I can mount

the lift so that it cannot be removed in the direction of movement of the walker.

Accordingly, a further object of my invention is to provide novel mechanical means for preventing separation between the heel and lift in the walking direction.

A further object of my invention is to provide novel locking means which will automatically increase its locking effect when an object normally tending to disengage the lift is encountered.

There are other objects of my invention which together with the foregoing will appear in the detailed description of the invention to follow.

Figure 1 is a perspective view of a preferred form of my invention.

Figure 2 is a developed view of the lift member.

Figure 3 is a developed view of the heel member.

Figure 4 is a cross section through 4—4 of Figure 1.

Figure 5 is a cross section through 5—5 of Figure 4.

Figure 6 is a cross section through 6—6 of Figure 4.

Figure 7 is a perspective view of a modified form of my invention.

As shown in Fig. 1, the main heel section 1 carries on its surface 2, a member 3. Member 3 consists of any material preferably a metal having the proper tensile and mechanical strengths for securely interlocking the heel section 1 with a lift to be described hereinafter. The metal preferably used is an annealed clock spring steel of high carbon content. The member is first formed in the shape to be described and thereafter tempered to give it the desired permanent spring action and durability.

The entire member 3 is contained within the edges of the heel section to which it is secured by prongs 4 integral with the member 3 or any other suitable means. Prongs 4 are driven into the section 1 by a pressing operation. Extending along the central portion of the member 3 from its rear end towards its front end, the member has been embossed as at 5 to a height to be described hereinafter to form a pocket with the surface 2 for the purpose to be described hereinafter. The rear end of the member 3 is cut away to form sloping edges extending from the open end of the pocket as shown at 6 and 7.

The two opposite outer symmetrical ends of 50 the edge of member 3 are turned up as at 8 and 9. Intermediate these turned-up edges 8 and 9 an integral right angle bend or flange 10 fits over the breast portion 11 of the main section 1. This right angle bend 10 is of a predetermined 55

length to provide an automatic means for properly placing the member 3 on the surface 2 between the breast and opposite edge of the heel.

Member 3 functions, as will be described, to

5 secure heel section 1 to the lift 12. The lift 12 is countersunk on its contacting surface 13 with

10 the heel section 1 to a depth of the overall thickness of all the metal lying between section 1 and

lift 12 which, in the present illustration, is ap-

proximately two thicknesses of the member 3.

Secured in the countersunk area 14 is a member 15 preferably of the same size, material and

gauge as member 3 and fitting snugly into the

15 depression 14. A section 16 of the member 15

has been removed, the size and shape of this

removed section being substantially equal to the

size and shape of the embossed section 5 and

10 forming a receptacle therefor as will appear

hereinafter.

20 Extending from the end 17, there is a tongue

18 integral with the member 15. As shown, the

tongue 18 is turned on itself at 17 along the full

25 width of member 15 to form a re-entrant section,

the tongue extending above the cut away portion

20 and being of the proper length, width and

shape to fill in and snugly fit the pocket formed

25 by the embossed section 5. The tongue 18 and

the corresponding embossed pocket 5 is made

30 sufficiently long to give the maximum leverage

or bearing surface. The limits are determined,

however, by the cut away portion which in turn

is limited to insure necessary strength at 19 in

35 the member 15. At the turned end 17 of the

member 15, sloping shoulders 21 and 22 are pro-

vided. The size and shape of shoulders 21 and

25 22 are designed to engage the corresponding

edges 6 and 7 of the member 3 when members 3

30 and 15 are interlocked.

At the front end of the member 15, two sym-

40 metrically turned up flanges 23 and 24 are pro-

vided which are arranged to engage with the

raised edges 8 and 9 of members 3. The width

45 between the turned up flanges 23 and 24 is equal

to the width of the flanges 10 and which is equal

50 to the separation of the turned up ends 8 and 9.

The lift is countersunk at 26 from the edge of the

metal between the flanges 23 and 24 to the breast

55 edge of the lift to a depth and width correspond-

ing to the shape and thickness of the flange 10

to provide a tight fitting edge at this point. The

member 15 is also preferably secured to lift by

50 prongs 25 integral with and extending from the

edges of member 15. A single pressing operation

forces and clinches these prongs into the leather.

55 Although prongs are described as securing

means, it will be understood that any other suit-

able means such as nails may be used.

In order to attach the lift 12 to the main heel

60 section 1, the lift 12 is placed with its engaging

face in opposing relation with the surface 2 of

the heel section 1 and the rear end of the mem-

ber 3 disposed in advance of the breast edge of

the lift. The tongue 18 is inserted in the open

65 end of the pocket 5. The lift is now moved for-

ward, the tongue sliding into place in the pocket

and guiding the forward movement of the lift

until the breast end of the lift 12 is in alignment

70 with the breast end of the main heel section 1.

At this point, the shoulders 21 and 22 of the

lift member 15 are in bearing engagement with

75 the corresponding edges 6 and 7 of member 3

and the forward movement of the lift has, ac-

cordingly, been automatically brought to a stop

when the breast edges of main section and lift

75 are in alignment.

The sides 28 and 29 on the lift member 15 ex-
tending from shoulders 21 and 22 to flanges 23
and 24 are now juxtaposed above sides 31 and
32 of member 3. The cut-away portion 16 of the
lift member 15 is now occupied by the embossing
of member 3 and the tongue 18 fits snugly in
the pocket 5.

5

The yieldable flanges 23 and 24 are juxtaposed
and above the corresponding flanges 8 and 9.
To lock the members, the lift is pressed firmly
10 against the main section. Flanges 23 and 24
yield under the pressure and roll over and under
the edges of flanges 8 and 9 respectively with
a snap action to lock the members in place.

15

It will be noted that all of the metal lies with-
in the depression formed in the lift 12, the metal
being evenly distributed so that there are just
two layers of metal at each point. The height
to which member 3 is embossed is equal to the
thickness of the tongue 18. Flanges 23 and 24
20 extend approximately to the surface of the lift.

25

With the members interlocked, if a foreign
body should impact with the lift, as the shoe is
being raised and moved forward in walking, the
force exerted on the lift will merely force the
flanges 23 and 24 into more firm engagement
with edges 8 and 9. Should the lift be acci-
dentially loosened, it would still be necessary to
raise the lift sufficiently to clear the embossing
and then move it backward until the tongue en-
tirely clears the pocket. Ordinarily, however, if
the lock is opened the wearer, on the next step,
will press the members into locking engagement
again.

30

To unlock the lift from the heel, any suit-
able tool is inserted in the countersunk portion
26 and the lift member is sprung until the flanges
23 and 24 slip over and away from edges 8 and
9. The lift is then raised to clear the embossing
and may then be removed by sliding the lift
40 backward until the tongue clears the pocket.

35

It will be noted that with this construction,
wide tolerances in the thickness of metal used
is permissible since each thickness of metal is
compensated for by proper depth of the coun-
45 tersunk sections.

40

The precision necessary with flange construc-
tions along the edges is avoided since no equiva-
lent flange constructions are used. The pocket
5 which takes the place of the flange is cen-
trally located and accordingly, one of the most
50 serious difficulties is overcome. When guiding
flanges along the edge of the lift are used, the
cover material used on the main heel section
and extending along the surface edge of the
55 section fills into the groove formed by the flanges
and interferes with the operation of the locking
member in the groove. The pocket in my con-
struction is made with the central or wood por-
tion of the heel section and facilitates operation
60 since there is no interfering matter. Furthermore,
the tongue in my construction can more
readily be inserted in the pocket than in con-
structions where two or more grooves must be
simultaneously contacted.

65

It should be further noted that the rear por-
tion of the metal on the main section is pro-
tected from the lift by the metal on the lift.
Accordingly, should the lift be worn completely
until metal is exposed, the metal on the lift
70 protects the metal on the heel.

75

The construction of the metal entirely within
the edges of the lift and heel insures a tight fit
of the lift and heel along the edges and thus pre-
vents the admission of any foreign matter.

75

- Although I have shown a right angle flange 10, it will be obvious that I may prefer not to use this guiding flange as shown in Fig. 7 and use any other means for positioning the member 3.
- 5 In Fig. 7 I have shown the members 3 and 15 turned through an angle of 90°. As already stated, the forces tending to accidentally separate the lift from the heel are in the direction the person is walking. With this modified construction, there is no possible way of separating the lift from the heel in this direction except by breaking the metal interlocking parts. At the same time, the members are readily assembled, locked and unlocked. This arrangement is possible with my construction as my members are independent of the size and shape of the heel and lift. Furthermore, no unsightly metal need be visible from the side of the shoes as would be necessary with prior constructions. In my construction, no visible means for fastening or disengaging is necessary.
- If desired, I may turn my parts 180° so that they are reversed in direction from that shown. Furthermore, although I have shown the countersinking in the lift, I may, if desired, reverse members 3 and 15, placing the former on the lift and the latter on the main heel section.
- It will be understood that although I have chosen to illustrate my invention as herein shown, the principle thereof may take other forms. It will also be clear that the invention may be applied to other types of the shoes, as for example, the rubber heels on men's shoes. Accordingly, I do not intend to be limited by the specific illustrations of my invention, but only as set forth in my claims which follow.
- I claim:
1. In combination, a main heel section having a regular symmetrically positioned member of uniform thickness secured thereto and a replaceable heel section having a regular symmetrically positioned member of uniform thickness secured thereto of substantially the same size and shape as said first mentioned member, the engaging surfaces of said members being arranged to provide a substantially uniform thickness throughout the overlapping and engaging portions of said members, one of said members having its inner portion removed and provided with an integral tongue extending from one end thereof and turned back, the other member being provided with a pocket adapted to fit into said cut away portion and to contain said tongue, said tongue being of substantially the same size and shape as said pocket, whereby said pocket provides a snug fit for said tongue, and said members dovetail.
  2. In combination, a main heel section having a regular symmetrically positioned member of uniform thickness secured thereto and a replaceable heel section having a regular symmetrically positioned member of uniform thickness secured thereto of substantially the same size and shape as said first mentioned member, the engaging surfaces of said members being arranged to provide a substantially uniform thickness throughout the overlapping and engaging portions of said members, one of said members having its inner portion removed and provided with an integral tongue extending from one end thereof and turned back, the other member being provided with a pocket adapted to fit into said cut away portion and to contain said tongue, said tongue being of substantially the same size and shape as said pocket, whereby said pocket provides a snug fit for said tongue, and said members dovetail.
  3. In combination, a main heel section having a regular symmetrically positioned member of uniform thickness secured thereto and a replaceable heel section having a regular symmetrically positioned member of uniform thickness secured thereto of substantially the same size and shape as said first mentioned member, the engaging surfaces of said members being arranged to provide a substantially uniform thickness throughout the overlapping and engaging portions of said members, one of said members having its inner portion removed and provided with an integral tongue extending from one end thereof and turned back, the other member being provided with a pocket adapted to fit into said cut away portion and to contain said tongue, said tongue being of substantially the same size and shape as said pocket, whereby said pocket provides a snug fit for said tongue, and said members dovetail, said tongue being provided with shoulders and said other member being provided with cut away edges bearing against said tongue shoulders.
  4. In combination, a main heel section having a regular symmetrically positioned member of uniform thickness secured thereto and a replaceable heel section having a regular symmetrically positioned member of uniform thickness secured thereto of substantially the same size and shape as said first mentioned member, the engaging surfaces of said members being arranged to provide a substantially uniform thickness throughout the overlapping and engaging portions of said members, one of said members having its inner portion removed and provided with an integral tongue extending from one end thereof and turned back, the other member being provided with a pocket adapted to fit into said cut away portion and to contain said tongue, said tongue being of substantially the same size and shape as said pocket, whereby said pocket provides a snug fit for said tongue, and said members dovetail, one of said sections being countersunk to compensate for said metal between said sections to permit the surface of said sections to be in pressing engagement with each other.
  5. In combination, a main heel section having a regular symmetrically positioned member of uniform thickness secured thereto and a replaceable heel section having a regular symmetrically positioned member of uniform thickness secured thereto of substantially the same size and shape as said first mentioned member, the engaging surfaces of said members being arranged to provide a substantially uniform thickness throughout the overlapping and engaging portions of said members, one of said members having its inner portion removed and provided with an integral tongue extending from one end thereof and turned back, the other member being provided with a pocket adapted to fit into said cut away portion and to contain said tongue, said tongue being of substantially the same size and shape as said pocket, whereby said pocket provides a snug fit for said tongue, and said members dovetail, one of said sections being countersunk to compensate for said metal between said sections to permit the surface of said sections to be in pressing engagement with each other, said members being entirely within the edges of said sections.
  6. In combination, a main heel section having a regular symmetrically positioned member of uniform thickness secured thereto and a replaceable heel section having a regular symmetrically positioned member of uniform thickness secured thereto of substantially the same size and shape as said first mentioned member, the engaging surfaces of said members being arranged to provide a substantially uniform thickness throughout the overlapping and engaging portions of said members, one of said members having yieldable flange means along one of its edges, the corresponding edge of said other member being raised to provide an engaging edge for said flange means, said one member having its inner portion removed and being provided with an integral tongue extending from one end thereof and turned back, the other member being provided with a pocket, said tongue being of substantially the same size and shape as said pocket whereby said pocket provides a snug fit for said tongue, and said members are in engagement with each other.

6. In combination, a main heel section having a regular symmetrically positioned member of uniform thickness secured thereto and a replaceable heel section having a regular symmetrically positioned member of uniform thickness secured thereto of substantially the same size and shape as said first mentioned member, the engaging surfaces of said members being arranged to provide a substantially uniform thickness throughout the overlapping and engaging portions of said members, one of said sections being countersunk to a depth sufficient to compensate for the thickness of the metal lying between the two sections, the member of said one section being secured within said countersunk portion and having yieldable flange means along one of its edges, the corresponding edge of the other member being raised to provide an engaging edge for said flange means, the one member having its inner portion removed and being provided with an integral tongue turned back above said cut away portion, the other member being provided with a pocket, said tongue being of substantially the same size and shape as said pocket whereby said pocket provides a snug fit for said tongue, and said members are in interlocking engagement.

7. In combination, a main heel section having a regular symmetrically positioned member of

uniform thickness secured thereto and a replaceable heel section having a regular symmetrically positioned member of uniform thickness secured thereto of substantially the same size and shape as said first mentioned member, the engaging surfaces of said members being arranged to provide a substantially uniform thickness throughout the overlapping and engaging portions of said members, one of said sections being countersunk to a depth sufficient to compensate for the thickness of the metal lying between the two sections, the member of said one section being secured within said countersunk portion and having yieldable flange means along one of its edges, the corresponding edge of the other member being raised to provide an engaging edge for said flange means, the one member having its inner portion removed and being provided with an integral tongue turned back above said cut away portion, the other member being provided with a pocket, said tongue being of substantially the same size and shape as said pocket whereby said pocket provides a snug fit for said tongue, and said members are in interlocking engagement, said tongue having sloping shoulders and said other member having cut away edges corresponding to and bearing against said shoulders.

JACK F. ESTERSON.
